UNITED STATES PATENT OFFICE.

JAMES K. TULLY, OF ST. LOUIS, MISSOURI, ASSIGNOR TO METALLIC INDUSTRIES, INC.,
OF ST. LOUIS, MISSOURI, A CORPORATION OF DELAWARE.

DESIGN FOR A CHILD'S VELOCIPEDe.

59,389.

Specification for Design.

Patented Oct. 11, 1921.

Application filed February 18, 1921. Serial No. 446,181. Term of patent 14 years.

To all whom it may concern:

Be it known that I, JAMES K. TULLY, a citizen of the United States, residing in the city of St. Louis, State of Missouri, have invented a new, original, and ornamental Design for a Child's Velocipede, of which the following is a specification, reference being had to the accompanying drawing, forming part thereof.

Figure 1 is a side elevation of a child's velocipede, showing my new design.

Fig. 2 is a plan view.

Fig. 3 is a front elevation; and

Fig. 4 is a rear elevation thereof.

I claim:

An ornamental design for a child's velocipede as shown.

JAMES K. TULLY.
